UNITED STATES PATENT OFFICE.

GORDON HOLLINGER, OF ST. JACOBS, CANADA.

THRASHING-MACHINE ATTACHMENT.

Application filed April 13, 1922. Serial No. 552,329.

To all whom it may concern:

Be it known that I, GORDON HOLLINGER, of St. Jacobs, in the county of Waterloo, Province of Ontario, Canada, a subject of the King of Great Britain, have invented certain new and useful Improvements in Thrashing-Machine Attachments, of which the following is a specification.

This invention relates to thrashing machines provided with pneumatic stacking devices.

It is desirable in such machines to provide means for moistening the straw to allay the dust which ordinarily accompanies the discharge of the straw, but the straw requires to be evenly moistened without excess in any one place otherwise heating and rotting is liable to occur when the straw is stacked. It is further important that no accumulation of water shall occur on any of the parts of the machine, as this would be liable to freeze up when the machine was used under low temperature conditions as is frequently the case in Western Canada.

I am aware that it has been proposed to moisten the straw by sprinkling it on the straw decks, but this has never proved to be successful in practice, and is subject to all the disadvantages hereinbefore referred to. My object therefore is to devise means for moistening the straw which will not be subject to these defects, and which will enable any desired content to be added to the straw.

I attain my object by providing the thrasher with a water pipe extending through the end of the fan casing of the stacker close to the fan shaft, which pipe extends a short distance within the casing and discharges, preferably, in a direction parallel to the fan shaft.

The invention is hereinafter more fully described and illustrated in the accompanying drawings, in which

Fig. 1 is a side elevation of part of a thrasher provided with my improvements; and

Fig. 2 a cross section through part of the same.

In the drawings like numerals of reference indicate corresponding parts in the different figures.

1 is part of the frame of the thrasher, and 2 one of the shafts of the same. This shaft may be any shaft which is constantly rotating with the thrasher, when in operation, and is used for the purpose which will

hereinafter appear. In the present case, the shaft chosen is one of the shafts for operating the straw decks. 3 is the casing of the pneumatic stacker, which as is now usually the case, is built into the machine. This fan casing is provided with the usual discharge pipe 4. In the casing is located the fan 5, which is secured to the fan shaft 6, which is suitably journalled at the ends of the casing. 7 is a pump preferably of the centrifugal type. 8 is a suction pipe and 9 a discharge pipe. The suction pipe will be led to any suitable source of water supply while the discharge pipe 9 is led to one end of the fan casing and extended through the end close to the shaft 2, and, in such a manner, as to discharge axially of the fan casing. The pump 7 is provided with a suitable pulley connected by means of a belt 10, with a pulley secured to the end of the shaft 2. While the machine is running the pump is also running and a constant stream of water is forced into the fan casing, and is there, by the action of the fan, broken up into a fine spray and thoroughly and evenly mingled with the straw. The pump will be so proportioned and its speed adjusted, so as to supply just the amount of water, which is found desirable, though the supply may be regulated within certain limits by means of the valve 11 in the supply pipe. I find in practice that all the water is taken up by the straw and none left to accumulate on parts of the thrasher. I find that any degree of moisture may be imparted to the straw even to the extent of causing heating and rotting, which is sometimes desirable when straw is to be used for fertilizing purposes.

What I claim as my invention is:—

1. A thrashing machine provided with pneumatic straw stacking means including a fan, an imperforate fan casing, an inlet passage leading to the eye of the fan casing, and a discharge pipe, in combination with a water supply pipe extending through the end of the casing opposite the eye and adapted to discharge axially of the casing towards the inlet passage so that the water is discharged against the incoming straw; and means for regulating the flow of water.

2. A thrashing machine provided with pneumatic straw stacking means including a fan, an imperforate fan casing, an inlet passage leading to the eye of the fan casing, and a discharge pipe, in combination with a

water supply pipe extending through one end of the casing opposite the eye and adapted to discharge axially of the casing towards the inlet passage so that the water is discharged against the incoming straw; means for regulating the flow of water; a pump secured to the thresher having its discharge connected to said pipe; and means for driving said pump from one of the constantly running shafts of the thresher.

3. A thrashing machine provided with pneumatic straw stacking means including a

fan, an imperforate fan casing, an inlet passage leading to the eye of the fan casing, and a discharge pipe in combination with a water supply pipe adapted to discharge water into the straw in the opposite direction to the movement of the latter as it enters the fan casing and before it passes to the discharge pipe.

Signed at Elmira, Ont., this 27th day of March 1922.

GORDON HOLLINGER.
